HEDGE TRIMMER

Joseph R. Mango, Midlothian, and Mario Giannola, Melrose Park, Ill., assignors to Portable Electric Tools, Inc., Geneva, Ill., a corporation of Illinois

Filed Nov. 30, 1965, Ser. No. 88,263

Term of patent 14 years

(Cl. D40—1)

FIGURE 1 is a top plan view of a hedge trimmer showing my new design. The broken line showing of the cutting blade is broken away for convenience of illustration;

FIGURE 2 is a side elevational view thereof;

FIGURE 3 is an end elevational view looking at the right-hand end of FIGURE 2;

FIGURE 4 is an end elevational view looking at the left-hand end of FIGURE 2; and

FIGURE 5 is a bottom plan view thereof.

The dominant features of the design are shown in full lines on the drawing.

We claim:

The ornamental design for a hedge trimmer, as shown and described.
